Patented July 24, 1928.

1,678,556

UNITED STATES PATENT OFFICE.

ERNEST D. COPSON, OF LINWOOD, PENNSYLVANIA, ASSIGNOR TO THE VISCOSA COMPANY, OF MARCUS HOOK, PENNSYLVANIA, A CORPORATION OF PENNSYLVANIA.

PUMP.

Application filed June 15, 1927. Serial No. 189,056.

My invention relates to pumps, and particularly to a pump for viscous liquids, such as viscose. The type of pump with which my invention deals is illustrated in the patent to Topham No. 1,480,425, and the object of my invention is to improve the construction of the latter to avoid certain weaknesses and defects inherent in that construction.

In the accompanying drawings—

Fig. 1 is a vertical section through a pump in which my invention is embodied in one form;

Fig. 2 is a section on the line 2—2, Fig. 1;

Fig. 3 is a plan view of the rotary piston 15 drive head;

Fig. 4 is a section on the line 4—4, Fig. 3;

Fig. 5 is a plan of the cam plate; and

Fig. 6 is a section on the line 6—6, Fig. 5.

It has been found that in practice the construction of the pistons shown in the Topham patent above mentioned, is the cause of considerable trouble since the repeated flexion of the piston stem results in breakage thereof and consequent temporary disablement of the pump. By providing a rigid piston rod and establishing an appropriate sliding connection between the piston and its rotary drive head, this difficulty is overcome. Certain other features of construction are 30 also improved.

The pump comprises a stationary hollow casing 15, from one end of which projects the drive stem 16 of a rotary block 17 which fits snugly within the chamber of the casing 35. The block 17 is provided with a plurality of piston bores 18 parallel with the axis of the block and having at one end lateral openings 19 which register with arcuate channels 20 and 21 formed in the inner face of the wall of casing 15. Through the latter an inlet passage 22 opens to the channel 20, and a discharge passage 23 opens to the channel 21. Suitable connections are made on one hand to the passage 22 from a 45 source of supply for the liquid to be pumped, for example viscose, and on the other hand to the passage 23 for the discharge of the liquid through a suitable conduit to a spinning nozzle of any appropriate type, as is well understood in the art.

Extending into the several bores 18 in rotary block 17 are solid plunger pistons 24, the outer ends of which are provided with ball heads 25 by which an actuating engagement with the rotary piston drive head 26 is

established. To receive the ball heads 25 of the several pistons, the drive head 26 is radially channelled at 27, the several channels being open at their outer ends and affording undercut slideways snugly fitting the ball heads 25, but permitting radial play of the piston heads therein. Preferably the ball heads of the pistons are connected to the plungers 24 by reduced necks 28 to accommodate the margins of the undercut channels 27 on the relative play of these parts during the drive of the pump.

A central cupped recess 29 in the drive head 26 receives a bearing ball 30, against which rests the thrust block 31 received in 70 an axial recess 32 in the rotary block 17. A spring 33 is engaged under stress between the bearing block 31 and the bottom of the recess 32 and serves not only to seat the block 17 against one end of the chamber of casing 75 15, but also to press the drive head 26 against the cam faced bearing plate 34 at the opposite end of the casing. To reduce wear I preferably provide the thrust block 31 with an inset 35 of specially hardened metal which 80 rests upon the ball 30.

The plate 34 is provided on its inner face with a cam surface 36 inclined to the axis of the pump. A bearing flange 37 on the plate engages the periphery of the drive head 26, 85 while a central hub 38 on the latter enters the bearing recess 39 formed in the cam face 36. The margin of the plate 34 is provided with arcuate slots 40 for the reception of screws 41 by which the plate is attached 90 to the pump casing 15. The slots 40 permit the rotary adjustment of the plate 34 to time the strokes of the pistons 24, and thus properly relate their operation to the intake and discharge channels 20 and 21 in the stationary casing 15.

The operation of the pump will be readily understood. When the block 17 is rotated by power applied in any suitable fashion to its stem 16 (for example through gear 42 100 fast thereon), the pistons 24 arranged in the bores 18 of the block are carried around therewith. The ball ends 25 of the pistons, severally engaging the piston drive head 26, cause the latter to rotate simultaneously. Inasmuch as the head 26 rotates on an axis inclined to the axis of the block 17, the pistons are reciprocated, drawing fluid into their respective bores 18 successively from the inlet port 22 and channel 20 during por- 110

tion of the revolution of the block 17, and forcing the liquid from the bores to the channel 21 and delivery port 23 during a succeeding portion of the revolution. The 5 pistons 24 being solid, no flexion thereof is possible. The slide engagement of their ball ends 25 in the slots 27 of the drive head 26, takes care of the radial play between these parts incident to their revolution on 10 axes inclined to each other. The undercut slideways 27 in the head 26 establish snug engagement with the ball ends 25 at all times, and insure smooth operation of the pump. The construction is rugged, serviceable, and free from danger of breakage.

I have indicated at 43 an opening through the casing 15 from delivery channel 21. This opening affords a connection on the delivery side of the pump to a pressure chamber (not shown) which serves to maintain a constant delivery pressure on the fluid, although the pump pistons have an intermittent action. This feature of the construction does not enter into my invention.

Modifications in details of construction 25 will readily occur to those skilled in the art which do not depart from the thoughts which underlie what I claim as my invention.

I claim—

In a pump of the type described, a hollow casing, a cam plate forming a closure for one end of the casing, a driven rotary block seated against one end of the casing, a piston drive rotor seated against the cam plate at the opposite end of the casing, pistons mounted in the rotor and working in the block and means for thrusting said block and rotor against their respective seats, said means comprising a bearing ball seated in one face of the rotor and a spring pressed plunger accommodated in the adjacent face of the block, said plunger having a hard metal inset engaging the bearing ball.

In testimony whereof I have signed my name to this specification.

ERNEST D. COPSON.
